AUTOMATIC HAIR WAVING COMB AND CLAMP DEVICE

Frank Zaccaro and Phokion C. Milosis,
New York, N. Y.Application February 16, 1938, Serial No. 190,756
Renewed February 11, 1939

17 Claims. (Cl. 132—31)

This invention relates to new and useful improvements in a combined hair waving comb and clamp device.

More specifically, the invention proposes the construction of a combined comb and clamp device characterized by a pair of cooperative clamp jaws pivotally connected together and having a comb interposed between the jaws and pivotally supported coaxially with the jaws.

Another object of this invention is to provide means for urging said jaws closed to clamp and hold a wave formed in a strand of hair and positioned upon said comb.

Still further it is proposed to form cam elements on the comb and engageable between the clamp jaws for holding the comb centrally of said jaws and firmly extended therefrom in the open condition of the jaws so that the comb may be passed through the hair for forming the wave.

Still further it is proposed to provide a means for holding the comb in various fixed positions with relation to its axis of pivoting for changing the distance between the edge of the comb and the bottom edges of the cooperative clamp jaws.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a combined hair waving comb and clamp device constructed according to this invention.

Fig. 2 is a plan view of Fig. 1.

Fig. 3 is an end elevational view of Fig. 1.

Fig. 4 is a sectional view taken on the line 4—4 of Fig. 2.

Fig. 5 is a perspective view of a portion of the comb per se.

Fig. 6 is an elevational view of an automatic hair waving comb and clamp device constructed according to a modification of the invention.

Fig. 7 is a sectional view on the line 7—7 of Fig. 6.

Fig. 8 is an enlarged detailed view of a portion of Fig. 7.

The combined hair waving comb and clamp device, according to this invention, comprises a pair of cooperative clamp jaws 10 pivotally connected together with each other and having handles 10^a by which they may be conveniently opened.

The clamp jaws are formed with a means for urging them closed and a comb 11 is interposed

between the jaws 10 and is pivotally supported coaxial with the jaws and is formed with cam elements 12 which are adapted to be engaged by the handles 10^a of the jaws 10 for holding the comb 11 centrally of said jaws and firmly extended therefrom.

The jaws 10 are formed from metal, Bakelite, or other similar material and have arcuately shaped bottom edges 10^b and are convexed away from each other to form a hollow between the adjacent faces thereof into which the comb 11 extends. Inwardly extending lugs 13 are formed at the top of the clamp jaws 10 and have openings 14 through which a pivot pin 15 extends for pivotally connecting together the jaws 10. The means for urging the jaws closed comprises a spring 16 coaxially mounted upon the pivot pin 15 and having one of its ends 16^a abutting against the top face of one of the handles 10^a and having the other of its ends 16^b abutting against the top face of the other handle 10^a. Thus the spring 16 tends to urge the handles 10^a apart for urging the jaws 10 together.

The comb 11 has the bottom ends of its teeth arranged in an arc 11^b corresponding with the shape of the bottom edges of the clamp jaws 10. The cams 12 are formed with foot portions 12^a which engage around the top edge of the comb 11, and the cams are formed with a centrally disposed opening 12^b through which the pivot pin 15 extends for pivotally supporting the comb 11 coaxially with the jaws 10. At the top the cams 12 are formed with sloping side walls 12^c which are adapted to be engaged by the inner face of the handles 10^a in the open position of the jaws 10 to hold the comb 11 centrally of the jaws and firmly extended therefrom so that it may be easily passed through one's hair for forming a wave.

The operation of this device is as follows:—

When it is desired to form a wave in one's hair the handles 10^a are urged together to open the clamp jaws 10 to the position shown by the dot and dash lines 10' in Fig. 3. When the jaws 10 are in their open position the inner faces of the handles 10 will bear against the sloping sides 12^c of the cam 12 for holding the comb 11 firmly extended from the jaws 10 so that it may be passed through the hair for forming the wave. After the wave has been completely formed on the comb 11 the handles 10^a are released to permit the springs 16 to again close the clamp jaws 10 upon the hair positioned upon the comb 11 for holding the wave in its fixed position.

According to the modification shown in Figs. 6—8 inclusive means is provided for holding the

comb in fixed positions with relation to the axis of pivoting for changing the distance between the bottom edge of the comb and the bottom edges of the jaws. The sides of the jaws 10 are also formed with openings 20 through which the air may circulate for drying the hair positioned upon the comb 11.

The means for holding the comb in shifted positions comprises a slot 21 formed in the cam 12' and into which a spring 22 is mounted. The end 22^a of the spring 22 is fixedly attached to one of the side walls of the slot 21. The other end 22^b extends upward along the other side of the slot 22 and is formed with half-circular depressions 23 arranged in aligned positions with complementary half-circular depressions 24 formed in the adjacent side wall of the slot 21. The half-circular depressions 23 and 24 are adapted to cooperate with each other to form an opening through which the pivot pin 15' is adapted to pass.

The pivot pin 15 may be shifted along the length of the slot so as to pass through either of the openings formed by the cooperating depressions 23 and 24 for holding the comb 11 in various extended positions with relation to the pin 15'. The handles 10^a are formed with inwardly and upwardly extending leaf springs 25 which are adapted to engage against the bottom edges of the cams 12' in the closed position of the clamp jaws 10 for holding the comb 11 centrally of the jaws. The handles 10^a are also formed with inwardly and downwardly extending leaf springs 26 which are adapted to engage the sloping side walls 12^c of the cam 12' in the open position of the clamp jaws 10 for holding the comb 11 centrally of the jaws and firmly extended therefrom so that it may be passed through a strand of hair for forming a wave. In other respects this form of the invention is similar to the previous form and similar parts may be identified by corresponding reference numerals.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:

1. A combined hair waving comb and clamp device, comprising a pair of cooperative clamp jaws pivotally connected with each other and having handles by which they may be conveniently opened, resilient means urging said jaws closed, a comb between said jaws and pivotally supported coaxially with said jaws, and cam elements mounted on said comb and engaged by said handles for holding the comb centrally of said jaws and firmly extended.

2. A combined hair waving comb and clamp device, comprising a pair of cooperative clamp jaws pivotally connected with each other and having handles by which they may be conveniently opened, resilient means urging said jaws closed, a comb between said jaws and pivotally supported coaxially with said jaws, and cam elements mounted on said comb and engaged by said handles for holding the comb centrally of said jaws and firmly extended, said cooperative clamp jaws being formed with curved bottom edges.

3. A combined hair waving comb and clamp

device, comprising a pair of cooperative clamp jaws pivotally connected with each other and having handles by which they may be conveniently opened, resilient means urging said jaws closed, a comb between said jaws and pivotally supported coaxially with said jaws, and cam elements mounted on said comb and engaged by said handles for holding the comb centrally of said jaws and firmly extended, said cooperative clamp jaws being formed with curved bottom edges, said comb being formed with a curved bottom edge running parallel with the curved bottom edges of said clamp jaws.

4. A combined hair waving comb and clamp device, comprising a pair of cooperative clamp jaws pivotally connected with each other and having handles by which they may be conveniently opened, resilient means urging said jaws closed, a comb between said jaws and pivotally supported coaxially with said jaws, and cam elements mounted on said comb and engaged by said handles for holding the comb centrally of said jaws and firmly extended, said clamp jaws being formed of metal, Bakelite, or similar material.

5. A combined hair waving comb and clamp device, comprising a pair of cooperative clamp jaws pivotally connected with each other and having handles by which they may be conveniently opened, resilient means urging said jaws closed, a comb between said jaws and pivotally supported coaxially with said jaws, and cam elements mounted on said comb and engaged by said handles for holding the comb centrally of said jaws and firmly extended, the pivotal connection of said clamp jaws comprising inwardly extending lugs interposed between said jaws and said handles and being formed with openings, and a pivot pin passing through said openings for pivotally connecting said jaws together.

6. A combined hair waving comb and clamp device, comprising a pair of cooperative clamp jaws pivotally connected with each other and having handles by which they may be conveniently opened, resilient means urging said jaws closed, a comb between said jaws and pivotally supported coaxially with said jaws, and cam elements mounted on said comb and engaged by said handles for holding the comb centrally of said jaws and firmly extended, the pivotal connection of said clamp jaws comprising inwardly extending lugs interposed between said jaws and said handles and being formed with openings, and a pivot pin passing through said openings for pivotally connecting said jaws together, said resilient means comprising a spring coaxially mounted on said pivot pin and having one of its ends engaging against the handle on one of said jaws, and the other of its ends engaging against the handle of the other of said jaws.

7. A combined hair waving comb and clamp device, comprising a pair of cooperative clamp jaws pivotally connected with each other and having handles by which they may be conveniently opened, resilient means urging said jaws closed, a comb between said jaws and pivotally supported coaxially with said jaws, and cam elements mounted on said comb and engaged by said handles for holding the comb centrally of said jaws and firmly extended, said clamp jaws being formed with openings in their sides through which air may circulate for drying the hair positioned upon said comb.

8. A combined hair waving comb and clamp device, comprising a pair of cooperative clamp

5 jaws pivotally connected with each other and having handles by which they may be conveniently opened, resilient means urging said jaws closed, a comb between said jaws and pivotally supported coaxially with said jaws, and cam elements mounted on said comb and engaged by said handles for holding the comb centrally of said jaws and firmly extended, and means for holding said comb in fixed positions in relation to its 10 axis of pivoting for changing the distance between the edge of the comb and the edge of said jaws.

15 9. A combined hair waving comb and clamp device, comprising a pair of cooperative clamp jaws pivotally connected with each other and having handles by which they may be conveniently opened, resilient means urging said jaws closed, a comb between said jaws and pivotally supported coaxially with said jaws, and cam elements mounted on said comb and engaged by 20 said handles for holding the comb centrally of said jaws and firmly extended, and means for holding said comb in fixed positions in relation to its axis of pivoting for changing the distance between the edge of the comb and the edge of said jaws, comprising springs mounted in slots formed in said cams, said springs being formed with inwardly extending half-circular depressions which are adapted to cooperate with complementary inwardly extending half-circular depressions formed in the adjacent side wall of said slots for forming openings through which the pivot pin of said clamp jaws is adapted to pass.

25 10. A combined hair waving comb and clamp device, comprising a pair of cooperative clamp jaws pivotally connected with each other and having handles by which they may be conveniently opened, resilient means urging said jaws closed, a comb between said jaws and pivotally supported coaxially with said jaws, and cam elements mounted on said comb and engaged by 30 said handles for holding the comb centrally of said jaws and firmly extended, and means for holding said comb in fixed positions in relation to its axis of pivoting for changing the distance between the edge of the comb and the edge of said jaws, and means on said handle for engaging against the sides of said cam elements for holding the comb centrally of said jaws.

35 11. A combined hair waving comb and clamp device, comprising a pair of cooperative clamp jaws pivotally connected with each other and having handles by which they may be conveniently opened, resilient means urging said jaws closed, a comb between said jaws and pivotally supported coaxially with said jaws, and cam elements mounted on said comb and engaged by 40 said handles for holding the comb centrally of said jaws and firmly extended, and means for holding said comb in fixed positions in relation to its axis of pivoting for changing the distance between the edge of the comb and the edge of said jaws, and means on said handle for engaging against the sides of said cam elements for holding the comb centrally of said jaws.

45 50 55 60

between the edge of the comb and the edge of said jaws, and means on said handle for engaging against the sides of said cam elements for holding the comb centrally of said jaws, said means comprising inwardly and upwardly extending leaf springs adapted to engage against the bottom of said cams in the closed position of said jaws.

5 12. A combined hair waving comb and clamp device, comprising a pair of cooperative clamp jaws pivotally connected with each other and having handles by which they may be conveniently opened, resilient means urging said jaws closed, a comb between said jaws and pivotally supported coaxially with said jaws, and cam elements mounted on said comb and engaged by 10 said handles for holding the comb centrally of said jaws and firmly extended, and means for holding said comb in fixed positions in relation to its axis of pivoting for changing the distance between the edge of the comb and the edge of said jaws, and means on said handle for engaging against the sides of said cam elements for holding the comb centrally of said jaws, said means comprising inwardly and downwardly extending leaf springs formed in said handles and adapted to engage against the top of said cams in the open position of said jaws.

15 13. A combined hair waving comb and clamp device, comprising a pair of cooperative clamp jaws pivotally connected with each other, means normally holding said jaws closed, and a comb supported between said jaws.

20 25 30 35 40 45 50 55 60

14. A combined hair waving comb and clamp device, comprising a pair of cooperative clamp jaws pivotally connected with each other, means normally holding said jaws closed, a comb disposed between said jaws, and means for holding the comb in fixed position when the jaws are opened.

15. A combined hair waving comb and clamp device, comprising a pair of cooperative clamp jaws pivotally connected with each other, means normally holding said jaws closed, and means for holding the comb in fixed position when the jaws are either opened or closed.

40 45 50 55 60

16. A combined hair waving comb and clamp device, comprising a pair of cooperative clamp jaws pivotally connected with each other, means normally holding said jaws closed, and a comb supported in a plane bisecting the angle of movement of the jaws.

17. A combined hair waving comb and clamp device, comprising a pair of cooperative clamp jaws pivotally connected with each other, means normally holding said jaws closed, a comb between said jaws, and means for holding the comb in a plane bisecting the angle of the jaws when the latter are open.
